UNITED STATES PATENT OFFICE.

WILLIAM E. ROBERTS, OF NEW YORK, N. Y., ASSIGNOR, BY MESNE ASSIGNMENTS, TO FOUNDATION OVEN CORPORATION, OF NEW YORK, N. Y., A CORPORATION OF NEW YORK.

COKE OVEN.

Application filed August 8, 1919. Serial No. 316,009.

To all whom it may concern:

Be it known that I, WILLIAM E. ROBERTS, a citizen of the United States, residing in the city, county, and State of New York, have invented certain new and useful Improvements in Coke Ovens, of which the following is a specification.

My invention aims to provide an oven which shall be evenly heated, economical and simple to construct and relatively easy to operate and keep in repair.

The oven is designed to operate without reversing the direction of the air and gases, and therefore requires no special reversing valves and operating mechanism such as is necessary with typical ovens of prior constructions.

In the accompanying drawings in which corresponding characters refer to corresponding parts in the several views—

Fig. 1 is a longitudinal section through the oven showing one tier of combustion and waste gas flues, and the waste gas and air ducts;

Fig. 2 is a transverse section on the line 2—2 of Fig. 1;

Fig. 3 is a detail horizontal section on the line 3—3 of Fig. 1;

Fig. 4 is a similar horizontal section through the flues on the line 4—4 of Fig. 1;

Fig. 5 is a longitudinal section through an oven of modified construction and Fig. 6 is a transverse section on the line 6—6 of Fig. 5.

Referring now to the embodiment of the invention illustrated in Figs. 1 to 4, the oven is supported on a mat or foundation 10 in which is formed a tunnel 11 for carrying off the burnt gases. This tunnel forms an outlet for all the waste gases emanating from the multiplicity of flues formed in the oven and to be hereinafter more fully described.

The oven consists of a structure of masonry having a plurality of parallel tiers of flues formed therein, each tier comprising a plurality of combustion and waste gas flues which flues are connected together at the top and at their bottom ends communicating

respectively with gas and air ducts and a waste gas duct. Coking chambers 50 are formed in the structure between the several tiers of flues. The several tiers of flues are identical in construction and, therefore, a detailed description of one tier will suffice for all. However, it is to be noted that the combustion chambers in one tier of flues are opposite the waste gas chambers in the adjacent tier so as to assist in the equal distribution of the heat within the oven. The several tiers of flues are connected with individual gas, air and waste gas ducts in a manner to be presently described.

Immediately above the foundation waste gas ducts 12, 13 and 14 are formed in the body 15 of the oven. The ducts 12 and 13 are connected to each other by a port 16 in the center of their length, the ducts 13 and 14 are connected at their opposite ends by ports 17 and 18 and the duct 14 is connected with the tunnel 11 by a port 19. Each tier of flues comprises a plurality of upright combustion flues 20 and waste gas flues 21 separated from one another by a wall 22. Gas is supplied to the several combustion chambers 20 through a gas duct 23 running longitudinally beneath each tier of flues and connected with the combustion flues by short branches 24. Nozzles 25 each having a restricted passage formed therein are placed in the branches when a gas of high thermal value is utilized. These nozzles can be removed so as to provide an orifice of more generous dimensions when a gas of low thermal value is to be utilized.

Combustion chambers 20 are also connected by branches 26 to the air duct 32 which furnishes a sufficient supply of fresh air to support combustion within the chamber 20. The top wall of each combustion chamber has an outlet port 27 formed therein and a sliding brick 28 is provided by means of which the effective area of the port 27 may be varied so as to regulate or equalize the temperature in the different parts of the oven. Naturally the central part of the oven will tend to retain a greater heat than the ends but by adjusting the position of

the sliding bricks the temperature of the entire oven can be readily equalized. Extension flues 29 are formed above the combustion flues 20 to permit the insertion of a suitable tool for manipulating the sliding bricks. The port 27 communicates with a short branch passage 30 which in turn communicates with the upper end of each waste gas flue 21 and each of said waste gas flues 10 is connected by a branch passage 31 leading to the upper waste gas duct 12. In operation gas is fed in through the duct 23 and flows by way of branches 24 into the several combustion chambers 20 where it is mixed 15 with air coming by way of branches 26 from the air duct 32. This air duct 32 is open to atmosphere at 33 and as shown in Figs. 1 and 3 makes a circuitous path around the waste gas ducts 12, 13 and 14 so that the air 20 is effectively preheated before entering the several combustion chambers. As the gases are burned in the combustion chambers they 25 flow upwardly and out through the port 27 and by way of branches 30 downwardly through the waste gas flues 21 and by way of branches 31 to the waste gas duct 12. The gas duct 12 is common to all of the waste gas flues in one tier. The gases coming from the several flues flow in the direction of the arrows in Fig. 1 through the flues 13 and 14 and are finally exhausted 30 into the tunnel 11, which may be connected with a stack or other suitable exhausting apparatus.

35 The flues in the several tiers are identical as above described as to gas, air and waste gas connections but are arranged as shown in Fig. 4 so that the combustion flues 20 in one tier are located opposite to the waste 40 gas flues in the adjacent tier. This arrangement assists in the equal distribution of the heat through the walls of the oven.

In Figs. 5 and 6 I have shown an alternative construction in which I provide two 45 combustion chambers 20^a and 20^b which communicate at their upper ends with a chamber 30^a which chamber in turn communicates with waste gas flue 21^a. The gas for combustion is supplied to the flues 20^a 50 and 20^b from a gas duct 23^a having branches 24^a leading to said combustion flues. The burnt gas flues 21^a are connected by branches 31^a to a waste gas duct 14^a which in turn is connected by branches 14^b and 14^c with the 55 tunnels 11^a and 11^b. Air to support combustion is supplied through a circuitous duct 32^a having branches 26^a communicating with the several combustion chambers. Sliding bricks 28^a are provided to regulate the flow 60 of gas through the ports 27^a so as to provide means for equalizing the temperature in different parts of the oven. This oven operates on the same general principles as the one previously described the gas and air flowing

upwardly in the direction of the arrows 65 through the flues 20^a and 20^b, the waste gases flowing downwardly and out by way of ports 21^a to the waste gas flue 14^a and thence by each of the branches 14^b and 14^c to the nearest tunnel 11^a or 11^b. 70

The coke ovens herein described are distinguished from the typical forms of ovens now in use in that the gases flow continuously in one direction. This eliminates the multiplicity of valves necessary in the typical forms of ovens and also eliminates the apparatus for simultaneously operating the several valves of the oven. 75

Though I have described with great particularity the construction of the specific embodiment illustrated it is not to be construed therefrom that I am limited thereto as changes may be made by those skilled in the art without departing from the invention as defined in the appended claims. 80

What I claim is:

1. A coke oven having a plurality of rows of combustion and waste gas flues which are connected at their upper ends, individual waste gas ducts adapted to carry off the waste gases from each row of combustion flues, said waste gas ducts each comprising a plurality of passages located in the same vertical plane above one another, the lowest passage communicating with an outlet tunnel 90 common to the waste gas ducts for all the rows of combustion flues, the several passages of each waste gas duct being connected by ports so that the waste gases from the combustion flues must flow successively 100 through said passages and to said tunnel, and individual air ducts serving each row of combustion chambers each air duct comprising a plurality of passages located on opposite sides of the waste gas ducts, the said air passages being so connected that the air supplied to each row of combustion flues must flow successively through the passage on both sides of the waste gas ducts so that it is thoroughly preheated. 105

2. A coke oven arranged to continuously circulate the air and waste gases in the same direction without reversal and without preheating the air in regenerators, including in combination combustion and waste gas flues 115 which are connected at their upper ends, waste gas ducts located below said flues, each of said waste gas ducts comprising upper, lower and intermediate passages 12, 13, and 14 respectively, the upper and intermediate passages 12 and 13 being connected by a port 16 near the center of their length and the lower and intermediate passages 14 and 13 being connected by ports 17 and 18 at their ends and the lower passage having a discharge 120 outlet 19 near the center of its length and said upper passage 12 being connected by branches 31 with said waste gas flues, and 125

air ducts 32 each comprising upper, a lower and an intermediate passage connected with each other and located adjacent to the upper, lower and intermediate passages 12, 13 and 14 of said waste gas ducts and adapted to circulate the air conveyed thereby around said gas ducts to thoroughly preheat it with-

out passing it through regenerators and branches 31 connecting said air ducts with said combustion flues.

In witness whereof, I have hereunto signed my name.

WILLIAM E. ROBERTS.
